Primary Examiner — Lauren D McVey

(57) **CLAIM**

The ornamental design for an equipment for distribution of electric power and data signals, as shown and described.

DESCRIPTION

FIG. 1.1: Perspective front, top, left view of an equipment for distribution of electric power and data signals;

FIG. 1.2: Perspective back, top, left view of the equipment;

FIG. 1.3: Right view of the equipment;

FIG. 1.4: Front view of the equipment;

FIG. 1.5: Back view of the equipment;

FIG. 1.6: Top view of the equipment;

FIG. 1.7: Rear view of the equipment;

FIG. 1.8: Left view of the equipment.

The broken lines in the drawings are directed to portions of the article which form no part of the claimed design.

1 Claim, 8 Drawing Sheets
